UNITED STATES PATENT OFFICE.

MARTIN NYSTROM, OF CHICAGO, ILLINOIS, ASSIGNOR TO THE BRUNSWICK-BALKE-COLLENDER COMPANY, OF CHICAGO, ILLINOIS, A CORPORATION OF DELAWARE.

DESIGN FOR A TOP PLATE FOR A PHONOGRAPH-MOTOR.

55,194.

Specification for Design.

Patented May 18, 1920.

Application filed December 3, 1919. Serial No. 342,277. Term of patent 14 years.

To all whom it may concern:

Be it known that I, MARTIN NYSTROM, a citizen of the United States, residing at Chicago, in the county of Cook and State of Illinois, have invented a new, original, and ornamental Design for Top Plates for Phonograph-Motors, of which the following is a specification, reference being had to the accompanying drawing, forming a part thereof, in which—

Figure 1 is a perspective view of a top plate for phonograph motors showing the design, and Fig. 2 is a sectional view.

I claim:

The ornamental design for a top plate for a phonograph motor as shown.

MARTIN NYSTROM.

Witness:

M. A. KIDDIE.
